GRINDING MILL

Myron S. Mischanski, Clifton, N.J.

Application February 17, 1958, Serial No. 715,646

6 Claims. (Cl. 241—162)

This invention relates to a grinding mill for grinding and pulverizing materials of various character. The invention particularly comprehends a grinding mill for pulverizing material to a relatively fine powder.

Another object of the invention is to provide a grinding mill having a grinding member rotatably mounted within a fixed grinding member and rotatably carried by the grinding member are a plurality of conical shaped crushing cones arranged within the fixed grinding member and adapted for rotation in a direction reverse to that of the grinding member.

Still another object of the invention is to provide a grinding mill of said character in which the crushing cones have smooth peripheral faces for crushing material between the same and the cooperating face of the fixed grinding member.

Still another object of the invention is to provide means for varying the pressure of the conical shaped cones against the fixed member.

Still another object of the invention is to provide a grinding mill of said character in which the rotatably mounted grinding member includes a conical shaped upper portion and a cylindrical shaped lower portion.

Still another object of the invention is to provide a grinding mill which is so constructed and arranged as to permit of the convenient removal or replacement of the parts thereof.

With the foregoing and other objects in view, reference is now made to the following specification and accompanying drawings in which the preferred embodiments of the invention are illustrated.

In the drawings:

Fig. 1 is a vertical sectional view of a grinding mill constructed in accordance with the invention.

Fig. 2 is a horizontal sectional view taken approximately on line 2—2 of Fig. 1.

Fig. 3 is a horizontal sectional view taken approximately on line 3—3 of Fig. 1.

Fig. 4 is a fragmentary vertical sectional view of a grinding mill embodying a modified form of the invention.

Fig. 5 is a schematic view of hydraulic means for varying the pressure of the crushing elements.

Referring to the drawings, the grinding mill illustrated in Figures 1 to 3 inclusive of the drawings includes a cylindrical housing 10 supported by and affixed to a support 11 of any desired character. Arranged within the housing 10 is a cylindrical casing 12 which is secured by screws 13 or equivalent fastening means to a top housing section 14 and with screws 15 or equivalent fastening means securing the housing section 14 to the housing 10.

Arranged below the casing 12 is an annular member 16 to which the housing 10 is affixed by screws 17 or equivalent fastening means and with screws 18 or equivalent fastening means rigidly fastening the annular member 16 to the support 11. The casing 12 constitutes a support for a plurality of vertically spaced rows of teeth

2

19 arranged with a plurality of the teeth 19 in each row disposed in circumferentially spaced relation. The teeth 19 are secured in threaded openings 20 in the casing 12 with the inner ends of the teeth projecting radially there-through.

With the housing 10 is a grinding member 21 affixed to a vertically disposed drive shaft 22 having a pulley 23 mounted thereon for turning the same by power means such as electric motor (not shown). The drive shaft 22 is journaled for rotation within a radial bearing 24 mounted in the top housing section 14 with the lower end of the drive shaft being enlarged and keyed or otherwise affixed to a flanged sleeve 25 forming the upper end of the grinding member 21. The grinding member 21 also includes a hollow frusto-conical shaped member 26 in which the flanged sleeve 25 is snugly fitted with the flange extending over the top thereof and secured thereto by screws 27 or equivalent fastening means. Secured to the frusto-conical shaped member 26 by screws 28 or equivalent fastening means is a cylindrical member 29 forming a part of the grinding member 21. The cylindrical member 29 is provided with a cylindrical bore 30 which opens into enlarged bore portions 31 and 32 opening through the top and bottom faces thereof in which are arranged a thrust bearing 33 and a radial bearing 34 respectively. Engaging against the upper race of the thrust bearing 33 is a head 35 of a centrally disposed shaft 36 mounted for guided reciprocatory movement in a sleeve 37 affixed at its lower end to a bottom section 38 of the housing 10. The upper end of the sleeve 37 is arranged within the inner race of the radial bearing 34.

The grinding member 21 is provided with a plurality of vertically spaced rows of teeth 40 arranged with the teeth in each row disposed in circumferentially spaced relation. The teeth 40 are formed on arcuate sectors 41, which sectors are secured to the conical shaped peripheral face of the member 26 by screws 42 or equivalent fastening means. The cylindrical member 29 is also provided with a plurality of vertically disposed rows of teeth 43 which are arranged with the teeth in each row disposed in circumferentially spaced relation. The teeth 43 are affixed to arcuate sectors 44 secured to the peripheral face of the cylindrical member 29 by screws 45 or equivalent fastening means. Each of the rows of teeth 40 and each of the rows of teeth 43 are disposed intermediate two of the rows of teeth 19 carried by the casing 12. This construction permits of the convenient removal of the sectors 41 and 44 for the replacement thereof with new teeth.

A particular feature of the invention is the use of a plurality of conical shaped crushing elements 47 preferably consisting of three such elements disposed 120° apart and provided with vertically disposed shafts 48 each journaled for rotation in radial bearings 49 and 50 arranged in a cylindrical cavity 51 in the cylindrical member 29 and with the upper end of the shaft bearing against a thrust bearing 52. The crushing elements 47 rotate with the rotation of the grinding member 21 and have independent rotation in an opposite direction by engagement of the conical shaped faces 54 thereof with the inclined peripheral face 55 of the annular member 16. Means is provided for varying the pressure of the crushing elements 47 against the peripheral face 55. For this purpose, the shaft 36 protrudes through the bottom section 38 of the housing 10 and is threadedly engaged by a manually rotatable nut 56 for exerting downward pressure on the grinding member 21. When the desired pressure of the crushing elements 47 against the peripheral face 55 is obtained for pulverizing the material to the desired comminution, a lock nut 57 is tightened on the shaft 36 against the nut 56 for maintaining the same in

set position. The bottom section 38 of the housing is secured by screws 58 or equivalent fastening means to the lower end of a cylindrical wall 59 forming a receiving chamber 60 for the ground material which is removed as desired through discharge openings 61 therein. The cylindrical wall 59 is affixed to the cylindrical member 16 by screws 62 or equivalent fastening means below the lower end of the peripheral face 55.

The top section 14 is provided with a plurality of openings 64 for feeding the material to be ground between the casing 12 and the grinding member 21. The material is progressively reduced in size as the same passes downwardly therebetween and upon reaching the peripheral face 55, the partly ground material is subjected to the crushing action of the crushing elements 47 rotating against the peripheral face 55 so as to finely pulverize the material. It is to be understood that the partly ground material slides down the peripheral face 55 between the crushing elements 47 which rotating with the grinding member 21 crushes the material to a fine powder before the material is discharged into the receiving chamber 60.

In the form of the invention illustrated in Figures 4 and 5 of the drawings, the grinding mill is illustrated in its application to a large commercial mill provided with hydraulic means for varying the downward pressure of the crushing elements.

In this form of the invention, the grinding mill includes a housing 67 affixed to a support 68 and having a grinding member 69 affixed to vertically disposed shafts 70 and 71 rotatably mounted in radial bearings 72 and 73 carried by a top housing section 74 and a spider 75 respectively. The grinding member 69 is similar in construction to the grinding member 21 in the previous form of the invention and includes a hollow frusto-conical shaped member 78 in which is secured a flanged sleeve 79 to which the enlarged inner end of the shaft 70 is splined. Secured to the frusto-conical shaped member 78 is a cylindrical member 80 which forms a part of the grinding member 69 and to which the shaft 71 is rigidly affixed.

The grinding member 69 is provided with a plurality of vertically spaced rows of teeth 81 formed on arcuate sectors 82 releasably secured to the member 78. The cylindrical member 80 is also provided with a plurality of vertically disposed rows of teeth 83 affixed to arcuate sectors 84 and the teeth 81 and 83 are disposed intermediate the rows of teeth 85 carried by a cylindrical casing 86 secured within the housing 67.

The grinding member 69 is also provided with a plurality of conical shaped crushing elements 87 which may consist of any desired number and, as illustrated, are three in number disposed 120° apart. The grinding member 69 has vertically disposed shafts 88, each journaled for rotation in radial bearings 89 arranged in a cylindrical cavity 90 in the cylindrical member 80 and with the upper end of each shaft bearing against a thrust bearing 91 similar to the arrangement of the crushing elements 47 in the previous form of the invention. The crushing elements 87 rotate with the rotation of the grinding member 69 and have independent rotation in an opposite direction by engagement of the conical shaped faces thereof with an inclined peripheral face 93 of an annular member 94 affixed to the support 68 below the casing 86.

The material to be ground is fed to the mill through openings 95 in the housing section 74 and is progressively ground by the rotation of the grinding member 69 and upon reaching the peripheral face 93 is crushed to comminuted form by the action of the crushing elements 87. The grinding material falls through openings 96 in the spider 75 formed integrally with the annular member 94 and falls into a receiving chamber 97 provided by the cylindrical wall 98. The cylindrical wall 98 is affixed by

screws or equivalent fastening means to the annular member 94 and has a bottom outlet 99.

A particular feature of the invention is the means for varying the pressure of the crushing elements 87 against the peripheral face 93 of the annular member 94. This is accomplished by a hydraulic piston 101 connected with the shaft 70 by a coupling 102 and with a thrust bearing 103 arranged between the upper end of the shaft 70 and the web of the coupling. The piston 101 is slideably disposed in an opening 104 in the wall of a hydraulic casing 105 affixed to a head 106 of a frame support 107 mounted on the housing section 74. Affixed to the inner end of the piston 101 is a piston head 108 and with openings 110 and 111 for admitting fluid under pressure to opposite sides of the piston head for movement of the piston 101 and shaft 70 in either direction by the pressure of the fluid admitted to the casing 105. The piston 101 extends through a packing gland 113 for preventing escape of the fluid through the opening 104 in the casing 105.

Hydraulic fluid is forced into the casing 105 on either side of the piston head 108 for varying the pressure of the crushing elements 87 against the peripheral face 93 by means of a pump 114 connected with a manually operated valve 115 by a fluid feed line 116. The suction side of the pump 114 is connected with a tank 117 and a fluid return line 118 extends from the valve to the inlet of the tank 117. The valve 115 is connected through one service port with the inlet 110 by means of a fluid line 119 and through the opposite service port by a fluid line 120 with the opening 111. The valve 115 is of standard construction and is provided with a manipulating member 121 which when moved in one direction supplies fluid to the casing 105 through the port 110 for moving the piston head 108 downwardly to increase the pressure of the crushing elements 87 against the peripheral face 93. When the operating member 21 is moved in the opposite direction, fluid will flow through the inlet 111 to move the piston head in the opposite direction. The line 120 operates as a return line when fluid is supplied through the line 119 and when fluid is supplied through the line 120, the fluid line 119 operates as a return line.

It will be understood that the inner race of the radial bearing 24 is splined on the shaft 22 to permit slight movement of the shaft with reference to the bearing when the nut 56 is turned on the shaft 36 to increase the pressure of the crushing elements 54 against the peripheral face 55. Likewise, in the modified form shown in Figure 4, the inner race of the radial bearing 72 is splined to the shaft 70 to permit of slight relative movement of the shaft 70 whereby the shaft may be moved downwardly by pressure of the fluid in the upper portion of the casing 105 to thereby increase the pressure of the crushing elements 87 against the peripheral face 93.

While the preferred forms of the invention are shown and described herein, it is to be understood that the same is not so limited and shall cover and include any and all modifications of the invention which falls within the purview thereof.

What is claimed is:

1. In a grinding mill, a cylindrical casing arranged on a vertical axis and having inwardly projecting elements on the inner periphery thereof, a grinding member having outwardly projecting elements on the outer periphery thereof, said grinding member being mounted for rotation within said casing for breaking up and pulverizing material between the elements on said grinding member and casing, said casing including a lower portion having a central opening therethrough provided with a peripheral inner face extending downwardly and inwardly in angular relation to the vertical axis of the casing, a plurality of radially arranged inverted conical shaped members mounted on shafts depending from said grinding member for relative rotation of said conical shaped

members with reference to said grinding member and disposed within the central opening in said lower portion, each of said conical shaped members having a narrow portion of its peripheral face disposed in engagement with the inner face of said lower portion with said narrow portions of said conical shaped members being arcuately spaced apart, and said conical shaped members rotating with said grinding member and having independent rotation by engagement of the peripheral faces thereof with the inner face of said lower portion for crushing material between said conical shaped members and said lower portion.

2. In a grinding mill, a cylindrical casing arranged on a vertical axis and having inwardly projecting elements on the inner periphery thereof, a grinding member having outwardly projecting elements on the outer periphery thereof, said grinding member being mounted for rotation within said casing for breaking up and pulverizing material between the elements on said grinding member and casing, said casing including a lower portion having a central opening therethrough provided with a peripheral inner face extending downwardly and inwardly in angular relation to the vertical axis of the casing, a plurality of radially arranged inverted conical shaped members mounted on shafts depending from said grinding member for relative rotation of said conical shaped members with reference to said grinding member and disposed within the central opening in said lower portion, each of said conical shaped members having a narrow portion of its peripheral face disposed in engagement with the inner face of said lower portion with said narrow portions of said conical shaped members being arcuately spaced apart, said conical shaped members rotating with said grinding member and having independent rotation by engagement of the peripheral faces thereof with the inner face of said lower portion for crushing material between said conical shaped members and said lower portion, and means for applying downward pressure on said grinding member for varying the pressure of said conical shaped members against the inner face of said lower portion.

3. In a grinding mill, a cylindrical casing arranged on a vertical axis and having inwardly projecting elements on the inner periphery thereof, a grinding member having outwardly projecting elements on the outer periphery thereof, said grinding member being mounted for rotation within said casing for breaking up and pulverizing material between the elements on said grinding member and casing, said casing including a lower portion having a central opening therethrough provided with a smooth peripheral inner face extending downwardly and inwardly in angular relation to the vertical axis of the casing, a plurality of radially arranged inverted conical shaped members mounted on shafts depending from said grinding member for relative rotation of said conical shaped members with reference to said grinding member and disposed within the central opening in said lower portion, each of said conical shaped members having a smooth peripheral face with a narrow portion of its peripheral face disposed in engagement with the inner face of said lower portion and with said narrow portions of said conical shaped members being arcuately spaced apart, and said conical shaped members rotating with said grinding member and each having independent rotation by engagement of the peripheral faces thereof with the inner face of said lower portion for crushing material between said conical shaped members and said lower portion.

4. In a grinding mill, a cylindrical casing arranged on a vertical axis and having inwardly projecting elements on the inner periphery thereof, a grinding member having outwardly projecting elements on the outer periphery thereof, said grinding member being mounted for rotation within said casing for breaking up and pulverizing material between the elements on said grinding member and casing, said casing including a lower portion hav-

ing a central opening therethrough provided with a smooth peripheral inner face extending downwardly and inwardly in angular relation to the vertical axis of the casing, a plurality of radially arranged inverted conical shaped members mounted on shafts depending from said grinding member for relative rotation of said conical shaped members with reference to said grinding members and disposed within the central opening in said lower portion, each of said conical shaped members having a smooth peripheral face with a narrow portion of its peripheral face disposed in engagement with the inner face of said lower portion and with said narrow portions of said conical shaped members being arcuately spaced apart, said conical shaped members rotating with said grinding member and having independent rotation by engagement of the peripheral faces thereof with the inner face of said lower portion for crushing material between said conical shaped members and said lower portion, and means for applying downward pressure on said grinding member for varying the pressure of said conical shaped members against the inner face of said lower portion.

5. In a grinding mill, a casing including a cylindrical upper portion arranged on a vertical axis and a lower portion having a central opening therethrough providing a peripheral inner face extending downwardly and inwardly in angular relation to the vertical axis of the casing, a grinding member including a frusto-conical shaped upper portion, a cylindrical intermediate portion affixed to said frusto-conical shaped upper portion and a plurality of radially arranged inverted conical shaped members rotatably mounted on shafts depending from said intermediate portion and disposed within the central opening in said lower portion of the casing and having their outer peripheral faces disposed in narrow engagement with said inner face of said lower portion, means mounting said grinding member for rotation within said casing, said cylindrical portion of said casing and said frusto-conical and cylindrical portions of said grinding member having cooperating means for breaking up and pulverizing material therebetween with the rotation of said grinding member, said conical shaped members rotating with said grinding member and having independent rotation by engagement of the peripheral faces thereof with the inner face of said lower portion for crushing the material between said conical shaped members and said lower portion, and said peripheral inner face of said lower portion being arranged to receive the pulverized material discharged by gravity from between the intermediate portion of said grinding member and the cylindrical portion of said casing.

6. In a grinding mill, a casing including a cylindrical upper portion arranged on a vertical axis and a lower portion having a central opening therethrough providing a peripheral inner face extending downwardly and inwardly in angular relation to the vertical axis of the casing, a grinding member including a frusto-conical shaped upper portion, a cylindrical intermediate portion affixed to said frusto-conical shaped upper portion and a plurality of radially arranged inverted conical shaped members rotatably mounted on shafts depending from said intermediate portion and disposed within the central opening in said lower portion of the casing and having their outer peripheral faces disposed in narrow engagement with said inner face of said lower portion, means mounting said grinding member for rotation within said casing, said cylindrical portion of said casing and said frusto-conical and cylindrical portions of said grinding member having cooperating means for breaking up and pulverizing material therebetween with the rotation of said grinding member, said conical shaped members rotating with said grinding member and having independent rotation by engagement of the peripheral faces thereof

with the inner face of said lower portion for crushing the material between said conical shaped members and said lower portion, said peripheral inner face of said lower portion being arranged to receive the pulverized material discharged by gravity from between the intermediate portion of said grinding member and the cylindrical portion of said casing, said grinding member having a non-rotary shaft operatively connected with the intermediate portion thereof, and cooperating means carried by said casing and said shaft for varying the pressure on said shaft to thereby vary the pressure of said conical shaped members against the inner face of said lower portion of the casing.
